UNITED STATES PATENT OFFICE.

WILLIAM MILLER, OF BOSTON, MASSACHUSETTS, ASSIGNOR TO HIMSELF
AND JOHN C. MURPHY, OF SAME PLACE.

IMPROVEMENT IN THIMBLES WITH GUARDED CUTTERS.

Specification forming part of Letters Patent No. 44,045, dated August 30, 1864.

To all whom it may concern:

Be it known that I, WILLIAM MILLER, of the city, county, and State of New York, have invented a new and useful Improvement in Sewing-Thimbles; and I do hereby declare that the following is a full, clear, and exact description thereof, which will enable others to make and use the same, reference being had to the accompanying drawings, forming part of this specification, in which—

Figure 1 is a side view of the thimble. Fig. 2 is a central longitudinal section of the same. Fig. 3 is a top view of the same.

Similar letters of reference indicate like parts.

This invention consists in the attachment to a sewing-thimble of a cutter or cutting-edge to cut thread.

It also consists in so applying a guard or shield in combination with such cutter as to protect its edge and to prevent it from cutting accidentally or catching in the work.

a is the cutter, consisting of a small knife-like piece of steel attached by soldering or otherwise to one side of the exterior of the thimble, near the bottom thereof, with its point upward and its cutting-edge toward the side of the thimble, the said edge being close to the thimble at the bottom and gradually increasing in distance therefrom toward the point. *b* is the guard or shield, consisting of a piece of plate metal of semi-elliptical or other suitable form, having a round point and rounded blunt edges, concave on one side and convex on the other, arranged to cover the cutter *a*, and attached by soldering or other-

wise to the lower part of the thimble, with its rounded point upward and projecting slightly beyond the point of the cutter. This guard or shield is also attached to the back of the cutter, and so serves to assist in securing the cutter firmly in place.

The thimble should be worn with the cutter on the back of the finger, where it will be out of the way in working. The thread is cut by placing it between the edge of the cutter and the thimble, across the edge of the former and near the bottom thereof, and drawing it toward its point.

Instead of making the guard or shield *b* of a separate piece, it may be made by indenting the interior of the thimble so as to produce upon the lower part of its exterior a projection of a form substantially like that of the guard or shield represented in Fig. 1, and then sawing through the said projection in a direction parallel with the side of the thimble, so as to detach it therefrom, except at the bottom. The projection thus separated is set or bent out from the side of the thimble and the cutter inserted into its concave interior and soldered into its place.

What I claim as new, and desire to secure by Letters Patent, is—

A thimble having the guard *b* attached or provided, in combination with the cutter or cutting-edge *a*, substantially as and for the purpose herein specified.

WM. MILLER.
